Primary Examiner — T Chase Nelson*Assistant Examiner* — Jonathan J. Han(74) *Attorney, Agent, or Firm* — Banner & Witcoff, Ltd.(57) **CLAIM**

The ornamental design for a shoe, as shown and described.

DESCRIPTION

FIG. 1 is a front perspective view of a shoe showing my new design; and,

FIG. 2 is a side view thereof.

The broken lines immediately adjacent to the shaded area define the bounds of the claimed design and form no part thereof. The hatching shown in the right panel depicts a mesh pattern spanning the panel, and no specific mesh pattern is claimed. The broken lines depicting the remainder of the shoe form no part of the claimed design.
